APPARATUS FOR APPLYING ABRASIVE TO
POLISHING WHEELS, BELTS, OR THE
LIKEJoseph S. Porter, New Haven, Conn., assignor to
D. & H. Scovil, Incorporated, Higganum, Conn.,
a corporation of Connecticut

Application March 17, 1937, Serial No. 131,461

20 Claims. (Cl. 91—18)

This invention relates to apparatus for applying abrasive to wheels or belts, and more particularly to a device for supporting the wheel or belt during the application of the adhesive, such as glue or cement, which is normally applied prior to the application of the abrasive, and then moving the wheel or belt to a position where it will come into contact with a quantity of the abrasive. Preferably the device will be so constructed that, if desired, a certain amount of pressure may be applied to the wheel when the abrasive is being applied, so that the latter may be forced into the adhesive under pressure.

Machines for this purpose have been made in the past, as illustrated, for example, by my prior Patents Nos. 1,775,110 of September 9, 1930, and 1,998,905 of April 23, 1935. The present invention relates to a device which has certain advantages over the devices shown in the prior patents referred to, and which also may be simple in construction and which may be operated rapidly and with considerable efficiency.

As the character and fineness of the abrasive applied to the polishing element, whether a belt or a wheel, depends upon the character of the work to be done, it is desirable that a machine of this kind be prepared for the application of various abrasive materials. To this end the present device is provided with a rotatable abrasive container, which may be readily removed from the machine and replaced with a new one, so that if several containers are kept on hand, each containing a different variety or grain size of abrasive material, it will be seen that the proper container may be readily placed upon the machine.

One object of the present invention is the provision of an apparatus for applying abrasive to belts, polishing wheels or the like, which will be relatively simple in operation and construction, and therefore relatively economical to manufacture.

A further object of the invention is the provision of a device of the character described having a movable or rotating abrasive container, which may be rotated with the surface of the abrasive therein in contact with the surface of the wheel or belt to be covered.

A still further object of the invention is the provision of a device of the character described having means for supporting a polishing wheel or belt and an abrasive container, so that the belt or wheel may be moved while in contact with the abrasive in the container, and may also be moved out of a position above the container for

the application of an adhesive material, such as glue or cement.

A still further object of the invention is the provision of a device of the character described, which shall provide a movable support for the polishing element, such as a wheel or belt, so that this element may have both the adhesive and abrasive applied while supported on the machine in a convenient and relatively simple operation.

To these and other ends the invention consists in the novel features and combinations of parts to be hereinafter described and claimed.

In the drawings:

Fig. 1 is a front view of an apparatus for applying abrasive to a polishing wheel embodying my invention; 15

Fig. 2 is a top plan view of the device shown in Fig. 1;

Fig. 3 is a modified sectional view taken generally on line 3—3 of Fig. 1; 20

Fig. 4 is a side elevational view partly in section on line 4—4 of Fig. 1;

Fig. 5 is a detail sectional view on line 5—5 of Fig. 3; 25

Fig. 6 is a detail sectional view on line 6—6 of Fig. 2;

Fig. 7 is a front elevational view similar to Fig. 1 showing the device arranged for applying abrasive to the polishing belt; 30

Fig. 8 is a top plan view of the device shown in Fig. 7; and

Figs. 9 and 10 are sectional views taken respectively on lines 9—9 and 10—10 of Fig. 8.

To illustrate a preferred embodiment of my invention, I have shown an apparatus comprising a base portion 10 having standards 11, 12 and 13 rising therefrom, within which standards are rotatably supported shafts 14, 15 and 16. Upon the shaft 15 is secured a disk-like supporting member 17 which removably supports the abrasive pan or container 18. Centrally disposed upon the support 17 is an upstanding cone frustum 19 which fits within a complementally shaped recess at the center of the pan 18. 35

The shaft 15 carries a sprocket wheel 20 driven by a sprocket chain 21 from a sprocket wheel 22 secured upon the shaft 16. The shaft 16 may be driven by the motor 23 through suitable reduction gearing contained in the gear box 24, the motor and gear box being supported by the upstanding member 13. On the upper end of the shaft 16 a crank 25 may be removably secured, so that, if desired, this shaft may be turned by hand. It will be understood, however, that the 55

crank is usually omitted when the device is driven by the motor 23.

Secured to the shaft 14 is a bracket arm 26 to the upper end of which is pivoted at 27 a link 28, which link passes through a slotted member 29 upon the upper end of the shaft 14.

To the free end of the link 28 is secured an arbor 30, this arbor being supported in a collar 31 and secured against rotation by means of the set screw 32. The arbor projects forwardly from the link 28, and is provided with a reduced portion 33 upon which is rotatably mounted a bushing 34, upon which bushing is supported a polishing wheel or work member 35, which is to be covered with abrasive. The reduced portion 33 of the arbor projects forwardly of the wheel, and upon the projecting end of this member is mounted a crank hub 36 carrying a manually operable crank 37. Beyond the crank hub a second sleeve 38 is also rotatably mounted on the projecting end of the reduced portion 33 of the arbor. The crank 37 enables the wheel to be positively turned by the operator when desired, and particularly during the application of the glue or cement to the wheel. The sleeve 38, rotatably mounted on the reduced end 33 of the arbor, may be grasped by the operator so that he may apply pressure to the wheel when in contact with the abrasive, if so desired. For the same purpose, a handle 39 is secured at the end of the link 28, so that the wheel may be pressed downwardly into the abrasive with both hands, if this is found necessary.

As shown more especially in Fig. 4, a bell crank lever 40 is pivoted at 41 to the lower portion of the slotted member 29, one arm of this bell crank lever extending upwardly and being provided with a tooth or lug 42 extending into the slot 43. As shown in Fig. 4, the link 28 lies below the lug 42. It may, however, be raised to occupy the upper part of the slot 43, and rest upon and be supported by the lug 42. In the lower position, as shown in Figs. 1 and 2, the link 28 supports the abrasive wheel or work member 35 in a position to contact with the abrasive in the pan or container 18.

The other arm extends forwardly from the pivot 41, and is connected by a rod 44 with a crank 45 mounted on the end of a rock shaft 46, which shaft extends across the machine and is designed to be rocked by the foot pedal 47. It will be understood that when the operator presses upon the pedal 47, the rod 44 will be drawn downwardly, and the member 42 will be withdrawn from a position within the slot 43. If, prior to the withdrawal of the lug 42, the link 28 has been in its upper position, it will now be permitted to drop by gravity into the lower position shown in Figs. 1 to 4.

A downwardly acting spring 48 is arranged to press upon a member 49 secured to the bell crank lever to maintain the lever in the position shown in Fig. 4, and it will always be returned to this position immediately that the foot pedal 47 is released. The arm 44 is provided at its upper end with a lost-motion connection with the bell crank lever 40, so that the latter may move when the link 28 is raised to its upper position without necessarily effecting movement of the rod.

To the shaft 14 is secured an operating arm 50 by means of the set screw 51, and an intermediate portion of this arm is designed to ride upon a segment 52 provided upon the upper portion of a bracket 53 supported upon the standard 12. At its free end the arm 50 is pro-

vided with a tubular portion 54 within which is rotatably mounted an upwardly extending operating handle 55. At its lower end this handle carries a crank arm 56 connected by a link 57 to a plate 58 pivoted at 59 upon the arm 50. On the lower surface of this plate are a pair of spaced downwardly projecting pins 60 and 61, designed to straddle the segment 52, and to enter notches 62 and 63 provided in lateral surfaces of the segment. These notches are upon opposite sides of the segment, one of them being adjacent the inner end and the other adjacent the outer end.

It will be apparent that if the handle 55 is rotated in a clockwise direction, as shown in Fig. 15 3, the plate 58 will be moved to the right, thus withdrawing the pin 61 from the notch 63 in the segment 52, and the arm 50 may then be moved along the segment from the full line position shown in Fig. 3 to the dotted line position shown 10 therein, in which position the pin 60 engages in the notch or recess 62 to releasably hold the arm 50 in its adjusted position. This movement of the arm also swings the shaft 14, bracket arm 25 26, and link 28, as will be explained hereinafter.

Upon the shaft 16 is rotatably or swingably mounted a bracket 65 which supports at its outer end the container for the adhesive material such as glue or cement, which is applied to the wheel before the application of the abrasive. This container may be swung from the full line position shown in Fig. 2 to the dotted line position shown in this figure, the first position being an out-of-the-way position occupied by the container while the abrasive is being applied, and the other being 35 the position assumed when it is desired to apply adhesive to the wheel, which is at that time also in the dotted line position shown in Fig. 2. Attached to the bracket is a guard 67 which is contacted by the end of the arm 50 when this 40 arm is in the full line position shown in Fig. 2, in order that the container 66 will be positively held in the out-of-the-way position. The contact of this member with the guard 67 also serves to swing the container to this position when the 45 arm is swung from the dotted line to full line position in Fig. 2.

It is desirable to provide means for maintaining the surface of the abrasive in the container 18 of substantially the same contour as will complement the contour of the periphery of the polishing wheel, so that the abrasive will be evenly applied over the entire surface of the wheel. To effect this result a scraper plate 68 is mounted to extend downwardly in the container 18, the lower edge of this plate being of the proper contour desired and being adapted to contact the abrasive in the container prior to the contact of the polishing wheel therewith. This scraper 68 is secured to a carrier 69 supported by a sleeve 70 mounted upon the shaft 16, and by an arm 71 which engages the upper part of the shaft 15. The holder 69 is provided with downwardly extending wings 72 and 73, shown more especially in Fig. 6, these wings lying forwardly of the plate 68 with respect to the direction of rotation of the container 18, and serving to draw the abrasive inwardly toward the central portion of the scraper plate, so that it will be properly contacted and spread out by the latter during the rotation of 70 the container.

The operation of the device may be briefly described as follows: The polishing wheel 35 is placed upon the arbor 30, as described, with the link 28 in its uppermost position in the slot 43, 75

in which position it is supported by the lug 42. The handle 55 is then given a slight rotation to release the pin 61 from the notch 63 of the segment 52, and the arm 58 is swung toward the operator, as viewed in Fig. 1, so that the polishing wheel moves from the full line position to the dotted line position shown in Fig. 2. The adhesive container is likewise moved from its full line to the dotted line position, shown in this figure, and the adhesive applied to the wheel, the wheel being manually rotated during this operation by the handle 37. It will be observed that the wheel has been withdrawn to a position wherein it does not overlie the container, so that none of the glue or cement will fall upon the abrasive. After the glue or cement has been applied, the arm 58 and polishing wheel 35 are returned to the full line positions shown in Fig. 2. The operator then steps upon the foot pedal 47, which withdraws the lug 42 from below the link 28 and permits the polishing wheel to drop by gravity on the surface of the abrasive in the container 18. The motor is then started and the container will be rotated, the polishing wheel also being rotated by frictional contact with the surface of the abrasive. When the wheel has been properly covered, the link 28 is manually raised to its upper position and the wheel removed.

In Figs. 7 to 10 of the drawings, I have shown a device adapted to be employed for the covering of endless polishing belts. This device is fundamentally like that just described for polishing wheels, and distinguishes from the latter mainly in the provision of means for supporting a belt in taut condition, and also in the location of the adhesive container at a different place. With these exceptions the device is like that described in connection with Figs. 1 to 6 of the drawings.

As shown more particularly in Fig. 10 of the drawings, the link 28, which is the same as that previously described, has secured at the end thereof the arbor 30 having the reduced end 33. Over this reduced end of the arbor is rotatably received a sleeve 75, upon which is rotatably supported the pulley 76 for supporting one end of the belt 77 which is to be covered. Mounted on the sleeve 75 is a handle or crank 78 designed to be used to apply pressure to the belt against the abrasive, and also designed to be used to engage with the pin 78a and rotate the sleeve 75 and the pulley 76 thereon. Upon the arbor 30 is secured a bracket 79 having a tubular portion 80 designed to receive in turn a sleeve 81 within one end of which a rod 82 is secured by any suitable arrangement, such as the bayonet joint 83. Adjacent the other end the sleeve 81 is slotted, as shown at 84, and through this slot passes the arbor 85 carrying a pulley 86, the arbor being secured to a rod 87 slidably mounted in the sleeve 81 and urged outwardly away from the rod 82 by the spring 88. The pulley 86 supports the other end of the belt 77. Also supported by the bracket 79 is a plate 89 over which the belt 77 is adapted to travel, and which supports the portion of the belt to which the adhesive is being applied, the adhesive being contained in the container 90 supported by a bracket 91 from the slotted member 29 at the upper end of the shaft 14.

Secured to the pulley 76 is a sprocket wheel 92 engaged by the sprocket chain 93, which is trained over a small sprocket 94 rotatably carried by a part of the bracket 79, and rotatable by the crank 95. Scrapers 96 and 97 may be provided to contact with the periphery of the pulley 76 to scrape from the periphery of this pulley any adhesive

which may drop thereon when the adhesive is being applied to the belt.

The operation of this device is substantially like that already described in connection with the device shown in Figs. 1 to 6 of the drawings. When the belt has been mounted upon the pulleys 76 and 86, the handle 55 may be moved to swing the arm 58 to one side of the abrasive container 18. The pulley 76 is then rotated by means of the crank 95 and associated sprockets 10 and chain 93 to move the belt 77 over the plate 89, the adhesive being applied thereto during this movement. After the glue or cement has been applied to the belt, if it is necessary to smooth it out, the pulley 76 may be rotated rapidly by means of the crank 78, so that the glue or cement will be spread thinly over the belt by a rapid operation.

After the adhesive has been applied to the belt, the arm 58 is swung toward the shaft 15 and the foot pedal 47 disposed to allow the link 28 to drop downwardly, as shown in Fig. 7, so that the polishing belt will be in contact with the abrasive in the container 18. The motor is then started and the belt covered with the abrasive. It will be noted that in the case of both machines the work member is held against the abrasive by the weight of this member and the parts which support it, including the link 28, and in addition, if desired, suitable pressure can be placed upon the work member to force it against the abrasive. It would also be obvious that, as the abrasive container 18 may be readily removed from and replaced upon the supporting table 17, if desired a number of these containers may be kept on hand containing various grades or grain sizes of abrasive, and the desired one used, depending upon the work for which the finished product is intended.

While I have shown and described some preferred embodiments of my invention, it will be understood that it is not to be limited to all of the details shown, but is capable of modification and variation within the spirit of the invention and within the scope of the appended claims.

What I claim is:

1. Apparatus for applying abrasive to a polishing element comprising a suitably supported upwardly opening container for the abrasive, means for rotating said container, and means for supporting a polishing element above the container with its surface in contact with the abrasive in the container.

2. Apparatus for applying abrasive to a polishing element comprising a suitably supported upwardly opening container for the abrasive, means for rotating said container, and means for rotatably supporting a polishing element above the container with its surface in contact with the abrasive in the container.

3. Apparatus for applying abrasive to a polishing element comprising a suitably supported container for the abrasive, means for rotating said container, and means for supporting a polishing element with its surface in contact with the abrasive in the container, said supporting means being vertically movable to move the polishing element out of contact with the abrasive.

4. Apparatus for applying abrasive to a polishing element comprising a suitably supported container for the abrasive, means for rotating said container, means for supporting a polishing element with its surface in contact with the abrasive in the container, said supporting means being vertically movable to move the polishing element

out of contact with the abrasive, and means to support said element in such raised position.

5. Apparatus for applying abrasive to a polishing element comprising a suitably supported container for the abrasive, means for rotating said container, and means for supporting a polishing element with its surface in contact with the abrasive in the container, said supporting means being vertically and horizontally movable to move 10 said polishing element away from said container.

6. Apparatus for applying abrasive to a polishing element comprising a suitably supported container for the abrasive, means for rotating said container, means for supporting a polishing element with its surface in contact with the abrasive in the container, said supporting means being vertically and horizontally movable to move 15 said polishing element away from said container, and means to hold said element in the position to 20 which it is moved.

7. A machine for applying abrasive to a polishing element comprising a support, an abrasive container mounted upon said support, means for rotating said support, means for movably supporting a polishing element, said means being disposed above said container and being pivoted to permit the polishing element to rest on the abrasive in the container under gravity.

8. A machine for applying abrasive to a polishing element comprising a support, an abrasive container mounted upon said support, means for rotating said support, means for movably supporting a polishing element, said means being disposed above said container and being pivoted 35 to permit the polishing element to rest on the abrasive in the container under gravity, said pivoted element being movable to a raised position, and means for holding said element in such position.

40 9. A machine for applying abrasive to a polishing element comprising a support, an abrasive container mounted upon said support, means for rotating said support, means for movably supporting a polishing element, said means being disposed above said container and being pivoted to permit the polishing element to rest on the abrasive in the container under gravity, said pivoted element being movable to a raised position, and means for holding said element in such 45 position, said pivoted element also being movable about a vertical axis to a position in which the polishing element is removed from said container.

50 10. Apparatus for applying abrasive to a polishing element, comprising a suitably supported container for the abrasive, means for rotating said container, means for supporting a polishing element with its surface in contact with the abrasive in said container, and a suitably supported 55 scraper contacting with the abrasive in said container during the rotation thereof.

60 11. Apparatus for applying abrasive to a polishing element, comprising a suitably supported container for the abrasive, means for rotating said container, means for supporting a polishing element with its surface in contact with the abrasive in said container, and a suitably supported 65 scraper contacting with the abrasive in said container during the rotation thereof, the lower edge of said scraper conforming to the surface of the polishing element to form the surface of the abrasive to the surface of the polishing element.

70 12. A device for applying abrasive to a polishing wheel comprising supporting means, a shaft 75

supported thereby, means for rotating said shaft, an abrasive container mounted on said shaft, an arm on the supporting means, a member pivotally supported on said arm and carrying an arbor adjacent one end thereof, said member being vertically movable about its pivot, means 5 removably holding said member in raised position, and said arbor being adapted to support a polishing wheel in upright position with its surface in contact with the abrasive in said container. 10

13. A device for applying abrasive to a polishing wheel comprising supporting means, a shaft supported thereby, means for rotating said shaft, an abrasive container mounted on said shaft, 15 an arm on the supporting means, a member pivotally supported on said arm and carrying an arbor adjacent one end thereof, said member being vertically movable about its pivot, means removably holding said member in raised position, and said arbor being adapted to support a polishing wheel in upright position with its surface in contact with the abrasive in said container, and said pivoted member being movable in a horizontal direction to swing said polishing 20 element away from said container. 25

14. A device for applying abrasive to a polishing wheel comprising supporting means, a shaft supported thereby, means for rotating said shaft, an abrasive container mounted on said shaft, 30 an arm on the supporting means, a member pivotally supported on said arm and carrying an arbor adjacent one end thereof, said member being vertically movable about its pivot, means removably holding said member in raised position, and said arbor being adapted to support a polishing wheel in upright position with its surface in contact with the abrasive in said container, said pivoted member being movable in a horizontal direction to swing said polishing 35 element away from said container, and a bracket 40 swingably supported on said frame and adapted to support a container for adhesive.

15. A machine for applying abrasive to a polishing belt comprising a frame, a vertically disposed shaft rotatably supported by said frame, means for rotating said shaft, an abrasive container supported on said shaft, supporting means carried by the frame above said container, and means on said supporting means to support an 45 endless belt in taut condition with a portion thereof in contact with the abrasive in the container. 50

16. A machine for applying abrasive to a polishing belt comprising a frame, a vertically disposed shaft rotatably supported by said frame, means for rotating said shaft, an abrasive container supported on said shaft, supporting means carried by the frame above said container, and means on said supporting means to support an 55 endless belt in taut condition, said supporting means being vertically movable to permit said belt to drop by gravity into contact with the abrasive in the container. 60

17. A machine for applying abrasive to a polishing belt comprising a frame, a vertically disposed shaft rotatably supported by said frame, means for rotating said shaft, an abrasive container supported on said shaft, supporting means carried by the frame above said container, and means on said supporting means to support an 65 endless belt in taut condition, said supporting means being vertically movable to permit said belt to drop by gravity into contact with the abrasive in the container, and said supporting 70 means being vertically movable to permit said belt to drop by gravity into contact with the abrasive in the container, and said supporting 75

means comprising a pivotally mounted member adapted to be swung about its pivot to a raised position, and means for releasably holding said member in such position.

5 18. Apparatus for applying abrasive to a polishing element comprising a suitably supported container for the abrasive, means for rotating said container about a vertical axis, and means for supporting a polishing element with its surface in contact with the abrasive in the container.

10 19. Apparatus for applying abrasive to a polishing element comprising a suitably supported container for the abrasive, means for rotating

said container, means for rotatably supporting a polishing element with its surface in contact with the abrasive in the container, and the axis of rotation of the container being at right angles to the axis of the support of the polishing element.

20. A machine for applying abrasive to a polishing belt comprising a frame, an abrasive container supported upon said frame to rotate about a vertical axis, and means on said frame to support an endless belt in taut condition, with a portion thereof in contact with the abrasive in the container.

JOSEPH S. PORTER.
